ALTAR

Frederick T. Paden, Collingswood, N. J.

Application December 16, 1947, Serial No. 143,166

Term of patent 3½ years

(Cl. D29—23)

To all whom it may concern:

Be it known that I, Frederick T. Paden, a citizen of the United States and residing at Collingswood, in the county of Camden, in the State of New Jersey, have invented a new, original, and ornamental Design for an Altar, of which the following is a specification, reference being had to the accompanying drawing, forming a part thereof.

The figure is a perspective view of an altar, showing my new design.

The back of the altar is substantially plain.

The dominant features of my design reside in the portion shown in full lines.

I claim:

The ornamental design for an altar, as shown and described.

FREDERICK T. PADEN.
